F. P. ANGELL.

DOOR CHECK.

APPLICATION FILED MAR. 23, 1917.

1,309,056.

Patented July 8, 1919.

UNITED STATES PATENT OFFICE.

FRED P. ANGELL, OF BATTLE CREEK, MICHIGAN.

DOOR-CHECK.

1,309,056.

Specification of Letters Patent.

Patented July 8, 1919.

Application filed March 23, 1917. Serial No. 156,866.

To all whom it may concern:

Be it known that I, FRED P. ANGELL, a citizen of the United States, residing at Battle Creek, in the county of Calhoun and 5 State of Michigan, have invented certain new and useful Improvements in Door-Checks, of which the following is a specification, the principles of the invention being therein explained and the best mode I have 10 contemplated for applying that principle, so as to distinguish it from other inventions for a similar purpose.

This invention relates to door checks, and more particularly refers to door checks in 15 which the cushion is affected by the compression of air and the reaction by means of a coil spring acting on a piston, the rod of which forms an uneven-faced rack engaging a segmental eccentric-shaped gear on the 20 axle on which the door operating arm is fitted, a check valve being fitted between the piston and its actuating rod in such manner that vacuum will not hinder the check from readily responding in opening a door, yet 25 furnish sufficient cushion in combination with the peculiarly designed piston and cylinder to allow the door to move slowly and silently when making its final closure.

Among other objects, the present invention 30 contemplates a door check of the character set forth that will be compact and neat in appearance, positive and silent in operation, and one that can be manufactured at a minimum expense. To these ends the invention 35 consists in the combination and arrangement of parts as will hereinafter be more fully described, shown in the accompanying drawings and defined in the appended claims, it being understood that 40 changes in the form, proportion, material and minor details may be resorted to without departing from or sacrificing any of the advantages thereof.

In the drawings, Figure 1 is a side elevation 45 of the door check applied to a door and its casing.

Fig. 2 is an end view of a door and its casing with the door check attached, the door being partially open.

Fig. 3 is a broken side elevation of the door check with its piston in a relaxed position, and as it would appear before opening a door.

Fig. 4 is a longitudinal vertical section.

Fig. 5 is a detail, broken section of the by-pass and its regulating needle valve.

Fig. 6 is a perspective view of the piston attaching stud.

Like marks of reference refer to corresponding or equivalent parts throughout the 60 different views, in which A represents a door; B, a door casing; and C, the check valve cylinder suitably attached to the door by means of screws through legs 1 forming a part of the cylinder casting. 65

The piston head 3 is arranged within the cylinder facing its removable closed head 2. This piston head is formed with a centrally-bored externally-threaded shank 4, around which the piston sucker or bushing 5 and its 70 resilient expanding ring 6 are placed, the bushing lying against the head with its curved rim flaring toward the cylinder head, the resilient ring 6 in turn being held against said bushing by an adjusting rimmed 75 nut spreader 7 fitted to the shank 4. The object of the aforesaid arrangement is to variably expand the piston bushing by turning the nut on the shank of the piston head, a means whereby wear of said bushing will 80 not interfere with its proper working. The ring may be of rubber, a coil of wire, or equivalent that will answer the purpose. The piston head as aforesaid arranged is fitted to a concentrically-disposed end of a 85 rack-faced piston rod 8 by means of a flanged-headed stud 9 screw-threaded into the end of the piston rod.

Between the end of the piston rod and a shoulder of the stud 9 a cupped disk 10 is 90 fitted, and about said stud within the cupped surface of said disk and a cupped-out surface of the piston-head 3, a flexible ring valve 11 is placed. This valve checks the escape of air in the space between the piston sucker 5 and the cylinder head 2 in the final closing of a door by stopping a passage or vent 13 leading from said space through the stud 9 to a chamber between the cupped surfaces of the disk 10 and piston head 3, 95 more especially after the piston has moved beyond a by-pass 12 leading from a point in close proximity to the rear of the piston into the cylinder to the rear of said piston when at its rearward stroke. The closing of the 100 vent 13 is effected by compressing the valve 11 between the cupped surfaces of the disk 10 and piston-head 3 by the sliding of the piston 5 on the stud 9 from air compression in the cylinder on the one hand, and the action of a spring 17 effecting an opposite movement to the piston rod and the disk 10 105 110

thereon, a reversal of the movement in the opening of a door releasing the vent and displacing any vacuum in the cylinder.

That the final closing of the door may be further facilitated, the cylinder is slightly funnel shaped at the end where the head 2 is screwed on, and as the piston sucker 5 nears the limit of its movement, compression in the cylinder is slightly reduced, yet having sufficient resiliency to ease the movement of the door in entering its jamb.

Fitted to intercept or regulate air through the by-pass 12, a needle valve D is screw-threaded into a boss formed on the cylinder for the purpose.

The piston adjusting collar 14 is fitted to slide on the concentrically disposed end of the rack piston rod 8. This collar is cupped, as at 15, where it faces the ring disk 10, so that when moved to its outward limit on the piston rod the disk 10 and said collar will be in alinement. Encompassing the piston rod and bearing against a rib 16 forming a guide-bearing for said piston rod and the rim of the collar 14, the coil-spring 17 is placed, its object being to return the piston to a normal position and close the door.

That the tension of the spring may be varied to meet conditions in the closing of a door, and still permit the piston to always move its full sweep in the cylinder, the piston rod is provided with a longitudinally-disposed hole to the side of its axis opposite its rack surface and fitted with a screw 18, the threaded end of which is screw-threaded into the movable collar 14.

The rack or toothed surface of the piston rod engages with the teeth of a segmental cam-shaped gear 20 arranged to one side of the piston, one end of its shaft 21 being seated in a removable screw-threaded bearing 22 fitted into a boss of the cylinder C, its opposite end extending through a screw-threaded bearing 23 in a boss on the opposite side of the cylinder and fitted with an arm 24, the arm 24 being hinged to a variably extensible arm 25 hinged to the door casing in the usual manner. The teeth on the piston rod are arranged in an irregular-faced manner, terminating in a raised uniform surface toward the piston extremity, for the purpose of geared contact with the cam-shaped segmental gear 20, the free end of the rack meshing with the gear 20 at its greatest circumferential throw, at which position the door is closed, an object in connection with the check valve 11 being not only to reduce the momentum of the door

nearing its closure, but also to prevent shock in closing.

An object in arranging a portion of the teeth at one end of the face of the gear 20 concentric with its shaft 21, and a corresponding meshing arrangement of teeth in the rack rod 8 nearest its piston, is to permit a door to be swung so that the hinged arms 24 and 25 may pass to or beyond alinement without accelerating or retarding the movement of the door opening and closing.

A cap 26 is fitted to the cylinder C, so that the piston rod 8 may have sufficient movement, and yet be covered without extending the cylinder itself for the purpose.

It will be obvious that by unscrewing the head 2 from the cylinder C the mechanism may be removed or replaced, as occasion may require, without taking the check from the door, an object of importance in mechanism of the character.

From the foregoing description taken in connection with the drawing, a more extended explanation of the operation and advantages of my invention is believed to be unnecessary.

Having, therefore, described my invention, what I claim as new and desire to secure by Letters Patent, is:

1. A door check, the combination of the cylinder, its head, a piston closing said cylinder and the piston rod attached to said piston, of the guide for said piston, a tension collar on said piston, the spring fitting between said guide and collar, and a screw passing through an offset of said piston rod into said collar for regulating the tension of said spring, substantially as specified.

2. In a door check, the combination with the cylinder, its head, a piston closing said cylinder and a piston rod, slidably fitted through said piston, of means to limit the movement of said piston on said piston rod, an annular cupped offset formed in said piston, an annular cupped offset formed in said piston rod, and a flexible ring valve interposed between the cupped surfaces of said piston rod and piston about a reduced portion of said piston rod, said piston rod having an opening leading from the space between its offset and said piston to the space between said piston and the closed head of said cylinder, as and for the purpose set forth.

FRED P. ANGELL.
